UNITED STATES PATENT OFFICE

LUTHER THEODORE VELEN, OF CLEBURNE, KANSAS.

DOOR-CHECK.

SPECIFICATION forming part of Letters Patent No. 535,033, dated March 5, 1895.

Application filed August 17, 1894. Serial No. 520,565. (No model.)

To all whom it may concern:

Be it known that I, LUTHER THEODORE VELEN, a citizen of the United States, residing at Cleburne, in the county of Riley and State of Kansas, have invented a new and useful Improvement in Door-Checks, of which the following is a specification.

My invention relates to an improved door-check of that class in which a caster-wheel is secured by a yielding bracket to the side of the door, at its lower edge, and means are provided for automatically blocking the rotation of the caster.

The objects of my improvement are, first, to provide improved means for blocking the caster in either direction; and, second, to provide improved means for securing the bracket to the door, all as hereinafter fully set forth.

The accompanying drawings illustrate my invention.

Figure 1 represents a front elevation of the device, in position on the door. Fig. 2 represents a side elevation of the same, showing the caster blocked in both directions. Fig. 3 represents a similar side elevation, showing the caster blocked in the direction of opening the door, only. Fig. 4 represents a front elevation of the bracket when removed from the door. Fig. 5 represents a side elevation of two forms of the blocking device.

In the drawings, 2, indicates the door. 3 indicates a bracket formed preferably of sheet metal, bent to form an obtuse angle. One end of said bracket, 4, is provided with a longitudinal slot, 5, and is adapted to be secured to the face of the door. The other arm, 6, of the bracket, is forked at its free end to form bearings for a shaft, 7 upon which is mounted a caster-wheel, 8. An opening, 9, intersecting with the slot 5, is formed at the angle of the bracket so as to permit the passage of a narrow clamping plate, 10, and the heads of screws, 11, 11, by means of which the bracket is secured to the face of the door. The blocking device consists, essentially, of a bracket, 12, suspended by means of a slotted bearing, 13, from the shaft on which the caster is mounted, at one side of the caster, having a pair of arms, 14 and 15, which project beneath the tread of the caster-wheel on opposite sides of a line drawn diametrically

through the center of the wheel. Bracket 12, is arranged to swing freely on the shaft 7, and also to have a slight radial movement thereon, relatively to the wheel.

Arms 14 and 15, are incased in some slightly yielding material, as rubber, or leather; and the periphery of the caster-wheel is preferably covered with rubber.

The device is secured to the face of the door, so as to be adjustable vertically thereon, by means of the clamping plate 10, and a pair of screws 11, 11 which are passed through holes in the clamping plate, securing it loosely to the door. Arm 4 of the bracket is then passed from above downward between the clamping plate and the face of the door, the clamping plate passing through the opening 9 in the bracket, and the screws entering the slot 5. Upon tightening the screws, the bracket is adjusted upon the door and firmly secured thereto, so that the periphery of the wheel may press with a greater or less force, as desired, upon the surface of the floor beneath the door, and arm 6, being elastic, is put slightly in tension.

The arrangement of arms 14, and 15, is such, that when both of the arms rest upon the floor, the tread of the caster rests upon the upper surfaces of the arms and is sustained thereby just clear of the floor. When the arms are in this position the caster is prevented from turning and the door is held at any desired angle. Upon a slight force being exerted to move the door in either direction, the bracket 3, in which the caster is mounted, yields sufficiently to permit the caster to ride over the obstructing arm, bracket 12 turning at the same time with the caster-wheel and assuming, when the door is moved toward closing, the position shown in Fig. 3; bracket 12 being prevented from turning with the wheel beyond a certain point, by a stop 17, formed upon arm 6. When the door is swung in the opposite direction, bracket 12 turns with the wheel and assumes first the position shown in Fig. 2, and then passes to the opposite side of the center of the caster from that shown in Fig. 3.

Bracket 12, with its arms 14 and 15, is formed, preferably, from a piece of wire, bent to the form required, as shown at the left

hand portion of Fig. 5, but it may be formed from sheet metal as shown at the right hand of Fig. 5.

It is obvious that, when it is desired to hold 5 the door in one direction only, bracket 12 may be formed with only one blocking arm.

I claim as my invention—

1. In a door-check, the combination of the bracket adapted to be secured to the face of 10 the door and having the yielding arm projecting laterally from the door, the caster-wheel mounted on a shaft in said arm, and the bracket suspended by means of a slotted bearing from the shaft upon which the caster- 15 wheel is mounted, said bracket having an arm which projects over the tread of the wheel and is adapted to engage the periphery of the wheel and the surface upon which the wheel rests, whereby the wheel is blocked at any 20 desired point, substantially as set forth.

2. In a door-check, the combination of the bracket adapted to be secured to the face of the door and having a yielding arm projecting laterally from the door, the caster-wheel mounted on a shaft in said arm, and the 25 bracket suspended by means of a slotted bearing from the shaft upon which the caster-wheel is mounted, said bracket having a pair of arms which project over the tread of the wheel on opposite sides of its center and are 30 adapted to engage the periphery of the wheel and the surface upon which the wheel rests, whereby the wheel is blocked from turning in either direction, at any desired point, substantially as set forth.

LUTHER THEODORE VELEN.
